UNITED STATES PATENT OFFICE.

ARNOLD S. BERTELS, OF TENAFLY, NEW JERSEY, ASSIGNOR TO WESTERN ELECTRIC COMPANY, INCORPORATED, OF NEW YORK, N. Y., A CORPORATION OF NEW YORK.

TESTING DEVICE.

Application filed July 9, 1923. Serial No. 650,299.

This invention relates to telephone exchange systems, and more particularly to an arrangement for testing the accuracy with which subscribers' message registers function.

In exchange systems in which all successful calls are charged against calling subscribers by message registers individual to the subscribers' lines, it is desirable to test the message registers from time to time to determine if they function accurately. Such information is not only of interest to the telephone company for showing if all successful calls are being counted so that the telephone company will be able to obtain full reimbursement for all service rendered to subscribers, but also serves to afford the telephone company basis for answering complaints entered by subscribers that they are being charged for more calls than they have actually made.

In order that this information may be readily and conveniently obtained, a portable test box is provided in the central office and equipped with apparatus and circuits for making all desired tests of subscribers' message registers. This test box is provided with suitable jacks, which may be connected by patching cords to frame jacks associated with subscribers' lines.

It is therefore the object of the present invention to provide a test box of the character above set forth for allowing the message registers of subscribers' lines to be readily and accurately tested.

Referring to the drawing, the test box forming the basis of this invention is disclosed at the right of the dot and dash line. This test box may be associated with either a line, such as A, terminating in the bank of a line finder as shown in the lower portion of the drawing; or with a line, such as B, terminating in a line switch. The invention is also equally adaptable to lines terminating in manual offices.

If the test box is used in association with lines of the line switch type only a portion of the equipment of the test box is employed, as will later appear, and if desired, two separate test boxes may be used, one having only the equipment shown in the upper right corner of the drawing for use with lines of the line switch type, and another having all of the equipment disclosed at the right of the

dot and dash line if used with lines of the line finder type. For convenience of illustration, however, the test box has been disclosed as of a universal type.

The subscriber's line A, which is one of a plurality of lines terminating in the multiple contacts of the line finder 100, on entering the central office is first directed to the main distributing frame MDF. From here it is connected to the terminal racks of the intermediate distributing frame IDF. At the intermediate distributing frame the line is connected and distributed to the desired terminals in the banks of line finder switches having access thereto. The line is equipped in the well-known manner with the usual line relay 101 and cut-off relay 102 for controlling the starting of the line finder 100, and with a message register 132. The message register in the usual establishment of connections is operated following the restoration of the subscriber's receiver to the switchhook by current of metering strength transmitted thereto over the lowermost brush of switch 100, the armature and back contact of line relay 101, terminals of frame IDF, thence through the winding of the register magnet to ground at the outer left armature and front contact of cut-off relay 102.

When it is desired to make tests of the message register 132 of the subscriber's line A, the shoe 105 terminating in cords 106, 107 and 108, 109 is attached to the line terminals at the intermediate distributing frame IDF. These cords, which terminate in the plugs 110 and 111, respectively, are then connected to jacks 112 and 113, respectively, of the test box. A reading is then taken of the message register 132 preliminary to the test thereof in order that the subscriber may not be charged for the additional registration incident to the test of the message register and also for the purpose of obtaining a reading as a starting basis for the tests to be conducted. After the test box has been connected to the line A, as above described, the test man throws the three position key 118 from the left position, in which the springs 133 are normally out of contact with their respective contacts, to the middle position, in which these springs close with their contacts, and thence to the right position, in which the springs 134 make with their alternate contacts. As soon as the springs 133 make with

their contacts, a circuit is closed through the right winding of relay 119, through the lower spring 133 and its contact to ground through the lower right spring 134 and its normal contact. If the line whose message register is being tested is at the time busy because of a call initiated thereby or because of a connection extended thereto, relay 119 becomes locked over a circuit extending through its left winding, left armature and front contact, the upper spring 133 and its contact, conductor 115, tip contacts of jack 113 and plug 111, conductor 109 to battery over the next to the lowermost brush of switch 100. Relay 119 is maintained energized over its holding circuit after key 118 is moved to its right position and at its right armature and front contact closes a circuit for the busy lamp 120 extending over an obvious circuit to ground at the lower spring 134 and its alternate contact.

The test man, noting the illumination of busy lamp 120, is apprised of the fact that the line is busy and that he should not proceed with the test of the message register thereof. He may thereupon disconnect the test box from the line A and connect it with another line, or he may wait until the busy line becomes idle. If the line is idle when connection is made therewith or becomes idle after connection therewith, relay 119, however, does not lock as previously described or unlocks when the line becomes idle. With relay 119 deenergized a circuit is extended from battery, through the winding of relay 121 and resistance element 135 in parallel, through the left armature and back contact of relay 119, the upper left spring 133 and its contact, conductor 115, tip contacts of jack 113 and plug 111, conductor 109, through the winding of cut-off relay 102 to ground. Relays 102 and 121 energize in this circuit, and battery potential is connected in a circuit parallel with the winding of cut-off relay 102 over terminals of the intermediate distributing frame to the multiples of test terminal 136 for marking the subscriber's line busy to any connector switch which may attempt to make connection therewith. The cut-off relay 102 of the subscriber's line upon energizing disconnects the winding of line relay 101 in the usual manner and connects ground over its outer left armature to one terminal of the message register magnet 132 preparatory to operating it. Relay 121 upon energizing closes a circuit for lamp 122, which upon illuminating indicates to the test man the idle condition of the subscriber's line. At the back contact of the right armature of relay 119 a circuit is also closed at this time from ground, through the lower spring of key 134 and its alternate contact, the right armature and back contact of relay 119 to battery through the winding of cut-

off relay 123 of the test box. Relay 123 connects the winding of relay 124 to the subscriber's line loop so that if at any time during the test the subscriber initiates a call, the test man will be signaled so that the test may if desired be discontinued during the time that the subscriber is calling. The circuit over which the relay 124 is energized if the subscriber initiates a call may be traced from battery, through the winding of relay 124, the right armature and contact of relay 123, conductor 116, sleeves of jack 112 and plug 110, conductor 106, terminals of distributing frames IDF and MDF, line conductor 103, thence over the subscriber's line loop, returning over conductor 104, terminals of the distributing frames, conductor 107, tips of plug 110 and jack 112, conductor 117 to ground at the left armature and contact of relay 123. Relay 124, energizing over this circuit, closes an obvious circuit for the calling lamp 125. The test man upon noting the calling signal 125 may disconnect the test box from the subscriber's line and connect it with another line or may wait until the call is terminated, restoring the key 118 to its left position for removing the busy potential from the sleeve conductor of the subscriber's line.

Assuming that the line is idle and that during the progress of the tests of the message register thereof the subscriber does not initiate a call, the test man first throws the "operate" key 130 and adjusts the slider connected with key 130 on the rheostat 127 until the milli-ammeter 126 records the current value which should be sufficient to operate the message register 132. The circuit over which current flows through the winding of the message register magnet 132 may be traced from battery through the contact of key 130, rheostat 127, milli-ammeter 126, conductor 114, sleeves of jack 113 and plug 111, conductor 108, winding of magnet 132 to ground at the left armature and contact of relay 102. This value of current is approximately .33 amperes. Following this the key 130 is restored and is then operated the necessary number of times to make the test, it being noted upon each operation of the key if the message register operates. A failure to operate upon each closure of key 130 would indicate an unstandard condition of the message register under test.

Following the completion of the test the "non-operate" key 129 is depressed and the slider connected thereto is adjusted on rheostat 127 until the milli-ammeter 126 records a current value which is the maximum which may be transmitted through the winding of the message register and not cause its operation. This current value is approximately .27 ampere. The key 129 is then restored and operated the necessary number of times

to make the test. If upon any operation of key 129 the message register 132 operates, an unstandard condition of the message register is denoted.

5 In order that the sensitivity of the message register magnet may be tested, it is intermittently operated and released at a fixed rate through the operation of the interrupter key 131. This interrupter key has 10 been disclosed diagrammatically as comprising a key and a rotary interrupter. In practice this key may be of the type disclosed in the patent to J. A. Wotton No. 1,288,358, issued December 17, 1918. This key comprises a rotary handle, which when depressed winds up and releases a spring motor. The spring motor when released drives an interrupter wheel through a chain of gears, which makes and breaks the interrupter contacts at the rate of one hundred times during a period of fifty seconds. In 15 making this test the test man first depresses the key 130 and adjusts the slider connected with this key on the rheostat 127 until the 20 milliammeter 126 records the test current value of approximately .344 ampere. The key 130 is then released and the handle of the interrupter depressed and released. Prior to the depression of the handle of the 25 interrupter key a reading is taken of the message register and immediately following the test a second reading is taken. If the 30 second reading is one hundred points higher than the first reading, it denotes that the 35 message register is functioning properly.

Following the completion of the above noted test the key 118 is restored to its left position and the test box is disconnected from the line A and connected with another 40 line, the message register of which is to be tested.

If a test of a message register of a line such as line B of the line switch type is to be conducted, the jack 159 of the test box is 45 connected by patching cord 160 to the test jack 156 of the line switch circuit of the line B. The cut-off relay 152 of the subscriber's line is then locked operated with a tool designed for that purpose and the line 50 switch is moved either electrically or by hand one step forward from its normal position. The "operate," "nonoperate" and "interrupter" keys 130, 129 and 131 are then 55 operated in the manner previously described for conducting the same tests of the message register magnet 153. The circuit of magnet 153, for these tests may be traced from battery, through contacts of the test keys of the 60 test box, rheostat 127, milliammeter 126, sleeve of jack 159, sleeve of plug 158, sleeve strand of cord 160, sleeves of plug 157 and jack 156, the second terminal and brush 154 in contact therewith of line switch 150, terminals of distributing frame IDF, winding 65 of message register magnet 153, the outer

left armature and front contact of cut-off relay 152 to ground through the right winding of the cut-off relay.

In addition to the tests previously described a holding test is conducted through 70 the operation of the "hold" key 128. In conducting this test the key 128 is first depressed and the slider associated therewith is adjusted on the rheostat 127 until the milliammeter 126 records the value of current which will just hold the message register magnet operated after it has first been energized by operating current. This current value is approximately .057 ampere. The key 128 is then released and the "operate" 75 key 130 depressed. After the "operate" key 130 has been depressed and the message register magnet 153 energized, the key 128 is depressed while key 130 is maintained depressed and is then held while key 80 130 is released. If the message register magnet is still maintained energized a proper operation thereof is indicated.

While the invention has been disclosed and described in connection with lines terminating in a full automatic exchange, it is obvious that message registers of lines terminating in a semi-mechanical office or in a manual office may be tested in substantially the same manner, it only being required that 95 the means for associating the test box with lines of the latter character be slightly modified.

What is claimed is:

1. In a telephone system, a subscriber's 100 line, a call charging device therefor, a test box, means for connecting said test box to said line, a source of current, and means in said test box for applying current of different prescribed strengths from said source 105 to said device for determining if said device is in standard operating condition.

2. In a telephone system, a subscriber's 110 line, a call charging device therefor, a test box, means for connecting said test box to said line, and a source of current, said test box comprising a rheostat and a plurality of keys for applying current of different prescribed strengths from said source to said device for determining if said device is in 115 standard operating condition.

3. In a telephone system, a subscriber's 120 line, a call charging device therefor, a test box, means for connecting said test box to said line, and a source of current, said test 125 box comprising means for applying current of different prescribed strengths from said source to said call charging device for determining if said device is in standard operative condition, and a rheostat and current measuring means for determining the prescribed current strengths.

4. In a telephone system, a subscriber's 130 line, a call charging device therefor, a test box, means for connecting said test box to

5 said line, and a source of current, said test
6 box comprising a key for applying current
7 of operating strength to said device, a key
8 for applying current of non-operating
9 strength, a key for intermittently applying
10 current of operating strength whereby it
11 may be determined if said device is in stand-
12 ard operating condition, and a rheostat and
13 current measuring means for determining
14 the prescribed current strengths.

15 5. In a telephone system, a subscriber's
16 line, a call charging device therefor, a test
17 box, means for connecting said test box to
18 said line, and a source of current, said test
19 box comprising line testing means for de-
20 termining the idle or busy condition of said
21 line, and means, upon the determination of
22 said idle condition, for applying current of
23 different prescribed strengths from said
24 source to said device for determining if said
25 device is in standard operating condition.

26 6. In a telephone system, a subscriber's
27 line, a call charging device therefor, a test
28 box, means for connecting said test box to
29 said line, and a source of current, said test
30 box comprising a line testing relay, sig-
31 nals controlled by said relay for indicating
32 the busy or idle conditions of said line, and
33 means, upon the determination of said idle
34 condition, for applying current of different
35 prescribed strengths from said source to said
36 device for determining if said device is in
37 standard operating condition.

38 7. In a telephone system, a subscriber's
39 line, a call charging device therefor, a test
40 box, means for connecting said test box to
41 said line, and a source of current, said test
42 box comprising a line testing relay, a line
43 relay, means controlled by said testing re-
44 lay if said line is idle for connecting said line
45 relay to said line, a signal controlled by said
line relay for indicating if said subscriber
initiates a call while said test box is con-
nected to said line, and means for applying
current of different prescribed strengths
from said source to said device for deter-
mining if said device is in standard operating
condition.

8. In a testing system for testing call
9 charging devices connected to subscribers' 50
lines, a test box, means for connecting said
10 test box to one of said subscribers' lines,
11 means to variably test the call charging de-
12 vice associated with said line, means for de-
13 termining whether said line is idle or busy, 55
14 and means to prevent the application of said
15 variable tests upon the call charging device
16 associated with a busy line.

17 9. In a testing system for testing call
18 charging devices connected to subscribers' 60
19 lines, a test box, means for connecting said
20 test box to one of said subscribers' lines,
21 means to variably test the call charging de-
22 vice associated with said line, means to in-
23 dicate that said test box has been connected 65
24 to a busy line, and means to prevent the
25 application of said variable tests upon the
26 call charging device associated with a busy
27 line.

28 10. In a telephone system, a subscriber's 70
29 line terminating in automatic switching ap-
30 paratus, a call charging device therefor, a
31 test box, means for connecting said test box
32 to said line, and a source of current, said
33 test box comprising a rheostat and a plu-
34 rality of keys for applying current of dif-
35 ferent prescribed strengths from said source
36 to said device for determining if said device
37 is in standard operating condition.

38 11. In a telephone system, a subscriber's 80
39 line extending through a distributing frame
40 and terminating in automatic switching ap-
41 paratus, a call charging device therefor, a
42 test box, a test clip for connecting said test
43 box to said line and switching apparatus 85
44 at said distributing frame, and a source of
45 current, said test box comprising a rheo-
46 stat and a plurality of keys for applying
47 current of different prescribed strengths
48 from said source to said device for deter-
49 mining if said device is in standard operat-
50 ing condition.

51 In witness whereof, I hereunto subscribe
52 my name this 29th day of June A. D., 1923.

ARNOLD S. BERTELS.
